DESIGN FOR AN ELECTRIC FOOD MIXER

Eric Gustav Feltman and Watson D. Harbaugh,
Chicago, Ill., assignors to A. F. Dormeyer Mfg.
Co., Chicago, Ill., a corporation of Illinois

Application August 18, 1939, Serial No. 86,764

Term of patent 7 years

To all whom it may concern:

Be it known that we, Eric Gustav Feltman and Watson D. Harbaugh, citizens of the United States, residing in the city of Chicago, in the county of Cook and State of Illinois, respectively, have invented a new, original, and ornamental Design for Electric Food Mixers, of which the following is a specification, reference being had to the accompanying drawing, forming a part thereof.

Fig. 1 is a side elevational view of an electric food mixer, showing our design;

Fig. 2 is a top plan view of the mixer;
Fig. 3 is a sectional view taken upon the line
3—3 of Fig. 1;

Fig. 4 is a sectional view taken upon the line
4—4 of Fig. 1.

We claim:

The ornamental design for an electric food mixer, as shown.
